Primary Examiner—Louis S. Zarfas

Assistant Examiner—Monica A. Weingart

(57) CLAIM

The ornamental design for a water cooler bottle cover, as shown and described.

DESCRIPTION

FIG. 1 is a front view of a water cooler bottle cover showing my new design;

FIG. 2 is a back view thereof;

FIG. 3 is a top view thereof; and,

FIG. 4 is an alternate front view thereof.

The broken lines showing of the water cooler and cups in FIG. 4, is for illustrative purposes only and forms no part of the claimed design.
